TOBACCO FEED FOR SCRAP BUNCH CIGAR MACHINES

Filed Sept. 4, 1937

UNITED STATES PATENT OFFICE

2,259,616

TOBACCO FEED FOR SCRAP BUNCH CIGAR MACHINES

Sigurd Clausen, Brooklyn, N. Y., assignor to International Cigar Machinery Company, a corporation of New Jersey.

Application September 4, 1937, Serial No. 162,461

18. Claims. (Cl. 131—21)

This invention relates to cigar machines and more particularly to improvements in devices for feeding tobacco to the bunch forming mechanism thereof.

Heretofore it has been the custom to make cigars from either long or short filler tobacco. It has now been proposed to make mechanically cigars or similar smoking articles from a type of tobacco which is neither of the above, but which in its appearance has many of the characteristics of the shredded tobacco commonly employed in cigarette manufacture. It is proposed, however, to use cigar tobacco and also, to cut or otherwise reduce it to shreds or pieces of greater widths than that used in cigarettes, although it is quite possible to employ tobacco cut to the same size as cigarette tobacco.

The usage of tobacco prepared in this manner results in considerable saving due to the elimination of stemming costs inasmuch as the whole leaves are cut to form the filler tobacco.

Naturally the feeding of proper quantities of this type of tobacco to cigar forming machinery presents considerable of a problem due to the fact that it tends to cling together in a mass and must be separated in order to feed it to the forming mechanism. It is, therefore, an object of this invention to provide a machine capable of effectively feeding shredded or otherwise prepared tobacco to a bunch machine for formation into elongated smoking articles.

It is a further object of the invention to provide means for feeding shredded tobacco and directing it into a receiving chamber, together with means for controlling the operation of the feeding means.

It is an added object of the invention to provide automatically operating mechanism for preventing the feed of tobacco, and also for locking said means against reinstatement of the feeding device when the machine indicates that the feed of additional tobacco is unnecessary.

The invention also consists of the provision of novel trip devices for controlling the tobacco feed.

The invention also consists of the provision of novel latch devices for controlling the tobacco feed, and means for resetting the latch.

It is an additional object of the invention to control the feed of tobacco to the bunch forming mechanism by providing a dual control for the tobacco feeding mechanism which advances tobacco from the source of supply.

The invention further includes novel latch mechanism which functions to lock the feeding

device against tobacco feeding movement, and means for tripping and resetting the latch.

The invention also consists in the provision of a measuring chamber and a charge forming unit wherein tobacco advanced from the chamber is formed into charges of suitable size, means for feeding shredded or other small cut tobacco to said chamber and control devices for limiting the flow of tobacco thereto.

10. The invention also includes means for forming suitable charges from tobacco fed to a measuring chamber having control devices associated therewith for controlling the movement of tobacco to the chamber.

15. The invention also contemplates the provision of latch mechanism for initiating and preventing the movement of shredded or similar small cut tobacco to a bunch forming machine wherein means are provided for measuring and cutting 20 bunch charges and wrapping said charges into bunches.

With these and other objects not specifically mentioned in view, the invention consists of certain constructions and combinations which will 25 be described hereafter and then set forth in the appended claims.

In the accompanying drawing which forms a part of this specification and in which like characters of reference indicate the same or like 30 parts:

Fig. 1 is a side elevation of a machine constructed in accordance with my invention;

Fig. 2 is a perspective view showing the chute which guides the tobacco from the hopper to the 35 charge measuring chamber;

Fig. 3 is an enlarged sectional view of the feed control mechanism with certain parts broken away;

Fig. 4 is a longitudinal sectional view on line 40 4—4 of Fig. 3;

Fig. 5 is a side elevation of an adjustable cam used on my machine.

Referring to the drawing, 10 indicates the frame of a cigar machine supporting a table 11 to which a rolling table 12 is operatively connected. A channel frame member 13 and another member 14 securely hold a tobacco feed mechanism, indicated generally at 15 and 15a, in place above the cigar machine. A hopper 16 is supported 45 by the frame 17 above the feed mechanism, and may be of a type similar to that disclosed in Patent No. 1,563,334, granted December 1, 1925, to W. B. Bronander, or in Patent No. 1,611,654 issued December 21, 1926, to C. V. Lindblad.

In the form illustrated, hopper 16 has a ta-

pered chute 18 (Fig. 2) to direct the shredded tobacco into a measuring chamber 32 of the type shown in Reissue Patent No. 20,334, granted April 20, 1937, to F. C. Gladeck et al. In the process of feeding from the supply contained in the hopper 16, the shreds or pieces of tobacco are separated from the mass and fed to chute 18 in a shower through the medium of a carding belt 19 trained over pulleys 20 and 21, mounted on shafts 22 and 23, respectively. The shaft 23 is driven by chain 24 which derives its motion from sprocket 25 fixed to cam shaft 26 journaled in bearings (not shown) in the cigar machine frame 10.

A feed chute 27 is pivotally secured to the frame member 17 at 28 and is automatically operated through a pin and slot connection at 29 to a link 30 in order to permit the tobacco to enter between the walls 31 of the measuring chamber 32, provided with a door 32a which is automatically opened at the proper time to allow a charge of tobacco advanced from the hopper to be fed into the measuring chamber.

The door 32a is mounted upon a shaft 35a to which is fixed lever 35 connected at 34 to a link 33, which link is also connected to a cam lever 36 at 36a. Lever 36 has mounted thereon a cam follower 37 which engages with a cam 38 mounted on shaft 26 as viewed in Fig. 1.

It will be observed, therefore, that cam 38 causes link 33 to operate door 32a through rotation of shaft 26, and due to the construction of cam 38 the door 32a moving against the tension of a spring 35b fixed thereto at 35c and at 35d to the machine frame, moves to open position, as shown in Fig. 1, just prior to the tilting of chute 27 at which time a charge of tobacco on the chute is ejected into the measuring chamber 32.

In Fig. 1 there has been shown in part the charge compressing plunger device which reciprocates in the measuring chamber. This device, which is constructed according to the disclosure in the Gladeck et al. patent above referred to, is provided with a compressor plunger 32b, which, operating in the compression chamber as described in said patent, is mounted on a rod 32c slidably mounted in a block 32d slideable on guides 32g. A spring placed around rod 32c bears against the plunger 32b, and also against the spring tension block 32e adjustably attached to rod 32f carried by block 32d. Attached to the free end of rod 32c is a finger 32h in which is adjustably mounted a threaded adjusting member 32j which is positioned to engage finger 49b which controls the feeding of the tobacco. Tobacco is fed from the chamber 32 by plunger 32b into a charge forming device C which in the illustrated embodiment is of the type shown in the Gladeck et al. patent, and is held therein by gate 12b. At the proper period in the machine cycle, knife 12a cuts off a charge of tobacco. The gate 12b is then swung downward, as shown in dotted lines in Fig. 1 and the charge is ejected by the plunger of the forming device onto the rolling apron belt 12, whereupon rolling pin 12c operates to roll the charge in a binder to form a bunch. Block 32c and its associated mechanism operates through the medium of lever 32k pivotally secured thereto and engaging a cam (not shown) as disclosed in the Gladeck et al. patent.

A pulley 39, which may be operated by a belt 40 from a motor (not shown) runs continuously to drive pulley 41 fixed to a shaft 42 by a belt 43, and through pulleys 44, 45 and 46, and the

belts 47 and 48, similar to the driving mechanism disclosed in Patent 1,563,334, above mentioned, to actuate a picker roller 50 which picks the tobacco from belt 19 and directs it downwardly into chute 18. A bevel gear 49 on the shaft 42 meshes with a bevel gear 49a fixed to a shaft 44a which carries the pulley 44 and drives the pulley 45. A clutch 51 of conventional design can be provided for starting and stopping the machine.

As stated previously, the belt 19 advances tobacco from the hopper into chute 18. In order to feed tobacco at the appropriate time, means are provided for imparting feeding movement to the belt when tobacco is needed in the compression chamber and for preventing its movement at all other times. Referring to Figs. 1, 3 and 4 it will be observed that clutch mechanism 52 controls the movement of the belt 19.

As described above, a chute 27 is pivotally mounted at 28 on the upright frame of the machine, and has connected thereto an adjustable link 30 pivotally secured to a block 30a fastened to shaft 63. A spring 27a secured to chute 27 and frame 14 normally holds the chute 27 against the chute 18 as shown in Fig. 1. When shaft 63 is rocked in a counterclockwise direction the chute 27 will discharge its contents into chamber 32. Clamped upon the shaft 63 is a lever 62 to which are pivotally secured at 87 and 84, respectively, two links 86 and 102. Link 86 is also connected to a cam lever 88 which is pivoted at 89 to the machine frame and is provided with a cam follower 90 engaging a cam 38b on shaft 26. A spring 88a secured to the lever 88 and to the frame (not shown) holds the cam follower 90 against cam 38b.

In order to vary the feeding period of belt 19, cam 38b, which controls the rocking movement of lever 91 and hence pawl 54, is formed in two relatively movable parts 38a and 38c, one loosely and the other fixedly mounted on shaft 26. These parts are adjustably held together by means of screws 92 passed through slots 92a formed in one of the cams, and secured in the other as shown in Figs. 1 and 5. Counterclockwise movement of lever 62 effects a discharge of chute 27 into chamber 32, as before mentioned.

Mounted upon a shaft 60 is a pawl 54 positioned to co-act with the teeth of a ratchet 100 forming a part of clutch 52 described hereinafter. Also fixed to shaft 60 is a lever 61 which extends downward and coacts with a rounded or cam portion 54a of a lever 64 loosely mounted on shaft 63. The prime function of lever 61 is to prevent reengagement of the clutch parts and prevent movement of the feeding belt 19 until the feed of additional tobacco from the hopper 16 is necessary for the formation of proper cigars. Lever 61 is held in this position by means of cam portion 64a of lever 64 (see Fig. 1). Also secured to shaft 60 is a lever 91 to which is pivoted at 94 the other end of link 102 previously mentioned. This end of the link is provided with a slot 95 in order to give the necessary lost motion connection required for the feed control mechanism. A spring 54a connected to one end of lever 91 at 54b, and also to the hopper at 54c normally tends to hold pawl 54 against ratchet 100. The movement of lever 62, through the described connections plays an important part in feeding of tobacco, inasmuch as the clockwise movement thereof effected by slotted link 102 engaging with pin 94 on lever 91 detaches the pawl

from the teeth of ratchet 100 against the tension of spring 54a to reengage the clutch and reinstitute the movement of belt 19. In order to insure the stoppage of the feed conveyor the cam surface 64a cooperating with arm 61 has been provided, as explained above.

The rotation of shaft 23 to operate feed belt 19 is effected by means of sprocket chain 24 and clutch mechanism 52. In Figs. 3 and 4 this mechanism is shown in detail and consists of a ratchet 100, and a flanged driving member 56, loosely carried by the shaft 23, provided with a hub on which is mounted and suitably secured sprocket 57 driven by chain 24. Fixed to shaft 23 is a driven clutch member 76 provided with a plurality of notches 78 in which are located balls or rollers 77 free to move therein between the projections 79 extending from the ratchet and pins 80 slidably fitted in recesses 103 in the clutch member 76, and forced to project therefrom by means of springs 104.

It can be seen, therefore, that the rotation of shaft 23 ceases whenever pawl 54 bears against the teeth of ratchet 100. This engagement causes the projections of ratchet 100 to force pins 80 into their recesses in driven member 76, and move rollers or balls 77 from contact with the flange of driving member 56. This disengagement of clutch parts is accomplished every time arm 61 bears against cam portion 64a of lever 64, and also at least once each cycle when the lower end of slot 95 of link 102 lifts lever 91 through pin 94, and swings the pawl 54 into coaction with a tooth of the ratchet. A handwheel 53 is fixed to shaft 23 to enable the machine to be turned over manually.

A latch mechanism is provided for controlling the movement of cam surface 64a. In the illustrated embodiment the rockshaft 69 which supports finger 49b has secured thereto a lever 67 having a free end provided with a nose 70. At its other end the lever is connected at 68 to an adjustable link 65, which link in turn is connected at 66 to an end of lever 64. Nose 70 of lever 67 is adapted to bear against lever 71 whenever the tobacco feed is incapacitated, and whenever more tobacco is to be fed the nose is moved along the lever arm 71a into engagement with a reduced or notched portion. A link 73 is pivotally connected to an end of lever 71 which is mounted on shaft 72. The other end of this link is connected at 81a to a lever swingable on a pin 82 on the side frame of the machine and provided with a cam follower 85 which trains on a cam 83 and through that medium lifts the lever 81 and hence swings the lever 71 once during each revolution of cam 83. In this manner arm 71a of lever 71 is swung at least once each cycle of the machine away from nose 70. A pin 71b is located in the path of movement of nose 70 and limits its free upward movement under the urging of a spring 74 secured to lever 67 at 68, and to the frame at 75. A spring 73a secured to lever 71 tends to hold lever arm 71a in contact with nose 70.

The feed mechanism 15a is operated by means of a sprocket 99 fixed to shaft 23 and provided with a chain engaging with a sprocket 99b on shaft 105. A pulley 101a cooperates with pulley 106 in supporting carded belt 107 in operative position. Chain 99a trained over sprockets 99b and 101 is responsible for the drive of belt 15a, power being supplied from shaft 23 which mounts sprocket 101.

In the operation of the machine, tobacco is

fed periodically from hopper 16 by means of carded belt 19 into chute 18 and is subsequently discharged into the compression chamber 32. As described hereinabove, shaft 26 which is continuously rotating, carries the adjustable cam 38b made up of two relatively movable parts. When the lever 88 is raised, due to engagement of follower 90 with the high portion of cam 38b, pawl 54 is moved into engagement with the teeth of ratchet 100 and the rotation of shaft 23, and the accompanying movement of feeding belt 19 ceases. When the follower 90 rides off the high portion of the cam, lever 91 is moved in the clockwise direction and pawl 54 is pulled from its engagement with the ratchet 100 and the normal drive of shaft 23 is reinstated. Normally, the positions of the cam members 38a and 38c are so adjusted that somewhat more than an amount necessary for one cigar bunch will be fed to the feed chute 18. It can be seen therefore that under these conditions there will be a gradual accumulation of tobacco in the compression chamber so that at certain cycles of the machine it will be unnecessary to feed additional tobacco to the feed chute 18. In order to prevent this feed when no tobacco is needed in the compression chamber, means have been provided for accomplishing this purpose. This control assumes the form of the above described cam surface 64a which holds the arm 61 in the position shown in Fig. 1, with pawl 54 bearing against the ratchet regardless of the position of lever 91. When additional tobacco is to be fed and before the normal disabling mechanism operated by cam 38b can become effective, it is necessary to move cam surface 64a from engagement with arm 61. This is accomplished by means of adjusting screw 32j carried by the plunger control mechanism which engages finger 49b mounted on shaft 69 and rocks lever 67 clockwise away from its engagement with notch 71a of lever 71. This movement disengages arm 61 from cam surface 64a and makes it possible for cam 38b to perform its prescribed functions, above mentioned. Upon return of the plunger 32b to the position shown in Fig. 1, the spring 74 moves nose 70 up into engagement with a pin 71b and moves the cam surface 64a up into position for re-engagement with arm 61. The above described movement of nose 70 into engagement with pin 71b takes place as a result of the counterclockwise movement of lever arm 71a, which releases the connection between the nose 70 and the notched portion of the lever arm 71a. In the rotation of cam shaft 26, cam 83 engages with cam follower 85 once for each revolution of shaft 86 and accomplishes the desired counterclockwise movement of lever 71 against the tension of spring 73. The latch mechanism is then set for feeding additional tobacco by reason of the fact that on the forward movement of plunger 32b, screw 32j will engage trip finger 48b, cause shaft 69 to rock, and nose 70 will move downwardly along the notched arm portion 71b of lever 71 whereupon cam surface 64a moves away from the tail of lever 61 and nose 70, either engages with the notch on lever arm 71a or travels downwardly along the notched portion depending upon the adjustment of link 65. Lever 61 is then free to move relative to cam surface 64a and link 86 can pull pawl 54 out of engagement with ratchet 100 so that clutch 52 is thrown into operation and belt 19 conveys tobacco from the hopper into receptacle 18.

The mechanism above described may be varied in construction within the scope of the claims for the particular device selected to illustrate the invention is but one of many possible concrete embodiments of the same. The invention is not therefore to be restricted to the precise details of the structure shown and described.

What is claimed is:

1. In a cigar machine, the combination with a traveling surface feeding shredded tobacco on its upper portion from a source of supply and a picker roll for removing tobacco from said surface, of a chute located to receive said tobacco, mechanism for stopping the movement of said surface once each cycle of the machine after an amount of tobacco in excess of a complete charge has been fed, and means acting independently of said mechanism for preventing resumption of movement of said surface during a succeeding cycle of said machine.

2. In a cigar machine, the combination with an endless traveling carded surface feeding tobacco from a source of supply and a picker roll for removing tobacco from said surface, of a chute located to receive said tobacco, mechanism for stopping the movement of said surface once each cycle of the machine after an amount of tobacco in excess of a complete bunch charge has been fed, and means acting independently of said mechanism for preventing resumption of movement of said surface during a succeeding cycle of said machine.

3. In a mechanism for feeding tobacco, the combination with a compression chamber, of means for feeding charges of tobacco each in excess of a bunch charge thereto, said means including a hopper, a carded belt feeding tobacco from said hopper to said chamber, a picker roller coacting with said belt, a reciprocating member in said chamber, control means on said member, and a device cooperating with said control means when the tobacco in said chamber reaches a predetermined minimum for operating said belt to feed tobacco from said hopper.

4. In a cigar machine, the combination with a tobacco receiving chamber, of means for feeding charges of shredded tobacco each in excess of a bunch charge to said chamber, said means comprising an endless carded feeding surface, means for moving said surface, a device for locking said surface against movement, means controlled by the quantity of tobacco in said chamber for reinstating the feeding movement of said carded surface, and means for varying the period of movement of said surface, including a cam, and means for adjusting the active driving face of said cam.

5. In a tobacco article forming machine having a tobacco supply hopper, and a bunch forming mechanism, a chute positioned to receive tobacco delivered from said hopper, a movable member closing said chute to retain tobacco delivered therein, an endless traveling surface for feeding charges of tobacco each in excess of a bunch charge from said hopper to said chute, a receiving chamber forming a part of said mechanism located below said chute and adapted to hold a plurality of bunch charges, a device for moving said member to open said chute, and thereby discharge the tobacco in said chute into said chamber, said device also being provided with means for stopping the feeding movement of said surface.

6. In a tobacco article forming machine having a tobacco supply hopper, and an endless belt for feeding shredded tobacco from said hopper,

- 10 a chute, a receiving chamber, a picker roller directing said tobacco from said belt into said chute and towards said chamber, means for intermittently moving said belt to feed charges of tobacco each in excess of a bunch charge from said hopper, means for preventing feeding movement of tobacco to said chamber when the tobacco therein is above a predetermined minimum quantity, and a trip device for reinstating the movement of said surface.
- 15 5. 15. In a tobacco handling machine provided with means for intermittently feeding charges of shredded tobacco each in excess of a bunch charge from a source of supply including an endless carded tobacco feeding belt, a picker roller 20 co-operating with said belt, a chute, and a pivoted plate closing said chute to retain charges of tobacco fed thereto, a chamber, means for periodically swinging said plate to discharge said charges into said chamber, and to lock said feeding 25 means against further feeding, a compressing plunger in said chamber, and control means associated with said plunger for reinstating the feed of tobacco to said chute.
8. 30. In a cigar machine, the combination with a tobacco receiving chamber and an intermittently moving conveyor for feeding shredded tobacco from a source of supply to said receiving chamber, of a chute directing said tobacco to said chamber, a door closing said chamber, means for 35 opening said door prior to the discharge of tobacco from said chute into said chamber, control means for instituting the feeding motion of said conveyor, said control means including a trip finger, a drive locking arm, a latch comprising 40 a lever having a nose, an arm member provided with a notch engaging said nose, a cam coacting with said arm and arranged to be swung into conveyor drive locking position, and means for rocking said finger and tripping said nose and notch connection to swing said cam from said position out of locking engagement with said arm.
9. 45. In a cigar machine, the combination with an intermittently driven conveyor for feeding shredded tobacco, of a receiving chamber arranged to receive tobacco fed from said conveyor, 50 a clutch for driving said conveyor, a ratchet forming a part of said clutch, a pawl co-operating with said ratchet to interrupt the drive of said conveyor, a locking device for holding said pawl in engagement with said ratchet when the drive is interrupted, control means associated with said device for reinstating the feeding movement of said conveyor, and means controlled by the quantity of tobacco in said chamber for actuating said control means.
10. 55. In a cigar machine having a device for conveying tobacco from a source of supply to a bunch forming machine, mechanism for controlling the movements of said device, comprising, a clutch driving said conveyor device, an arm movable to throw out and disconnect said clutch and thereby stop the movement of said device, a member for locking said arm in its clutch disengaging position, a movable trip finger, a latch coacting with said finger, a lever provided at one end with a cam, a link connecting said latch and said lever, means normally holding said cam and member in locking position, means operable when the tobacco in said machine falls below a predetermined minimum for moving said

finger to trip said latch and move said cam from contact with said member, thereby releasing said arm, and means for withdrawing said arm from said clutch to reinstate feeding movement of said device.

11. In a mechanism for forming tobacco articles having a hopper containing a supply of tobacco, a compression chamber and a feed chute for delivering tobacco towards said chamber, means for feeding charges of tobacco each in excess of a bunch charge from said hopper to said chute, said means including a carded belt feeding tobacco from said hopper to said chute, and a picker roller coacting with said belt, a reciprocating compressing member in said chamber, control means on said member, and a device co-operating with said control means when the tobacco in said chamber reaches a predetermined level for operating said belt to feed tobacco from said hopper.

12. In a cigar machine having means for feeding tobacco from a source of supply to a bunch forming unit, including an endless traveling conveying surface, and a chute arranged to receive tobacco discharged from said surface, a compression chamber located to receive charges of tobacco each in excess of a bunch charge from said chute, and mechanism for periodically moving said surface, comprising means for interrupting said movement, and locking means for preventing movement of said endless conveying surface and feeding of additional tobacco to said chute, said locking means including, a ratchet forming a part of said mechanism, a pawl, and means for holding said pawl and ratchet in engagement and said surface immovable until the quantity of tobacco in said chamber reaches a predetermined minimum.

13. In a cigar machine having a bunch forming member, a substantially horizontal tobacco receiving chamber arranged to hold a plurality of charges associated therewith, a feed chute delivering tobacco towards said chamber, an endless carded conveyor for feeding tobacco to said chute, and mechanism for controlling the movement of said conveyor, said mechanism comprising a clutch, a clutch release and locking device, means for moving said locking device into cooperation with said clutch to stop said conveyor whenever the tobacco in said chamber reaches a predetermined maximum, means for holding said device in clutch releasing position, a latch, a trip finger, means for moving said finger to trip said latch, and connections between said latch and device for reinstating the operative drive of said clutch.

14. In a cigar machine having a bunch forming unit, a substantially horizontal tobacco receiving chamber adapted to contain a plurality of charges associated therewith, a feed chute for delivering tobacco towards said chamber, an endless carded conveyor for feeding tobacco to said chute, and mechanism for controlling the movement of said conveyor, said mechanism comprising a clutch, a clutch release, and a locking device, means for moving said device into cooperation with said clutch to stop said conveyor whenever the tobacco

in said chamber reaches a predetermined maximum, means for holding said device in clutch releasing position, a latch, a trip finger, means for moving said finger to trip said latch, connections between said latch and device for reinstating the operative drive of said clutch, and means for resetting said latch.

15. In a tobacco article forming machine having a shredded tobacco supply hopper, a bunch forming mechanism, a chute positioned to receive tobacco delivered from said hopper, a member closing said chute to retain tobacco delivered therein, and an endless traveling surface for feeding charges of tobacco each in excess of a bunch charge from said hopper to said chute, a receiving chamber forming a part of said mechanism located below said chute and adapted to hold a plurality of bunch charges, means for moving said member to open said chute and thereby discharge the tobacco in said chute into said chamber, and means for separating bunch charges from the tobacco in said chamber.

16. In a cigar machine having a traveling shredded tobacco feeding surface, a chute, and a compression chamber adapted to receive tobacco from said chute, and a picker roller located adjacent the discharge end of said surface for separating and directing charges of tobacco each in excess of a bunch charge from said surface into said chute and towards said chamber, and means for controlling the feeding movement of said surface including a device for interrupting said feeding surface travel whenever said chamber contains a predetermined maximum quantity of tobacco.

17. In a tobacco article forming machine having a tobacco supply hopper, a bunch forming mechanism, and a chute positioned to receive tobacco delivered from said hopper, a movable member closing said chute to retain tobacco delivered therein, an endless traveling surface for feeding tobacco in excess of a bunch charge in a substantially continuous stream from said hopper to said chute, a receiving chamber forming a part of said mechanism and holding a plurality of bunch charges of tobacco located below said chute, a device for moving said member to open said chute and thereby discharge the tobacco in said chute into said chamber, and means for stopping the feeding movement of said surface when the quantity of tobacco in said chamber reaches a predetermined maximum.

18. In a cigar machine provided with an intermittently traveling shredded tobacco feeding surface, a chute, a charge receiving chamber arranged to hold a plurality of bunch charges of tobacco, a picker roller cooperating with said surface to feed charges of tobacco each in excess of a bunch charge into said chute and from said surface towards said chamber, means for separating individual bunch charges from the tobacco in said chamber, and means associated with said chamber for moving said surface to feed tobacco whenever the tobacco in said chamber reaches a predetermined minimum.

SIGURD CLAUSEN.
